[57] **CLAIM**

The ornamental design for a paper delivering scanner, as shown and described.

DESCRIPTION

FIG. 1 is a front elevational view of the paper delivering scanner showing our new design;
FIG. 2 is a rear elevational view thereof;
FIG. 3 is a top view thereof;
FIG. 4 is a bottom view thereof;
FIG. 5 is a leftside elevational view thereof;
FIG. 6 is a rightside elevational view thereof;
FIG. 7 is a perspective view thereof;
FIG. 8 is an enlarged sectional view thereof taken along line 8—8 of FIG. 3; and,
FIG. 9 is another perspective view thereof, in which a main body is separated from a base plate.
